UNITED STATES PATENT OFFICE.

JOSEPH R. W. MENGER, OF NEW YORK, N. Y.

LUBRICATOR.

990,895.

Specification of Letters Patent.

Patented May 2, 1911.

Application filed November 12, 1908, Serial No. 462,263. Renewed February 17, 1911. Serial No. 609,215.

To all whom it may concern:

Be it known that I, JOSEPH R. W. MENGER, a citizen of the United States, and resident of New York, in the county of New York and State of New York, have invented certain new and useful Improvements in Lubricators, of which the following is a specification.

This invention relates to improvements in 10 lubricators.

In the drawings:—Figure 1 is a side view of an implement constructed in accord with this invention, the door being shown in closed position. Fig. 2 is a side view from 15 an angle different from that shown in Fig. 1, showing the door as partly opened. Fig. 3 is a cross-section taken on the line 3—3. Fig. 4 is a section taken on the line 4—4, in Fig. 1 of drawing.

20 The principal objects which the present invention has in view are—First to provide a lubricator of the squirt-gun order wherein may be used alternately either grease or oil. Second to procure a mechanical construction 25 whereby the necessary force may be applied to the feed plunger when delivering grease; and whereby the plunger may be advanced or receded to accommodate the needs of this feed. Third to produce a construction 30 wherein a change to the use of grease or oil may be readily and quickly made.

With these objects in view the construction as illustrated in the drawing consists of a cylindrical barrel, 2, which is formed to 35 any desired diameter, the ends of which are open, and are threaded to receive the caps, 3 and 4. The latter of these caps is suitably provided with the spout, 5. The spout may be any desired length or shape and may be 40 replaced as is common with the lubricators. The cap, 3, is provided with a boss, 6, to form an elongated bearing to be provided with an internal thread, which in operation is engaged by the threaded shank of the 45 screw threaded nipple, 7. The barrel, 2, is provided in its side with an opening, 8, of suitable dimensions; which opening is provided to permit the filling of the interior of the barrel with heavy lubricant, such as 50 grease. This opening is closed by means of a door, 9, which is provided with hinge wings, 10, that are suitably mounted in hinged lugs, 11, 11. The lugs, 11, are usually cast on the barrel, but it will be understood 55 that if it is desired to construct the barrel of tubing or sheet metal, these lugs may be riveted or otherwise attached. At the other

end of the door it is secured in position by the nut, 12, threaded on the swing bolt, 13. This swing bolt is hinged on the barrel, 2, 60 and is adapted to swing up and over the yoke, 14, formed on the door, 9. The operation of the swing bolt is commonly understood.

When the door is closed and the swing 65 bolt is thrown in position, it may be desired to true the interior of the barrel so that the inner face of the door will conform to the cylinder of the interior of the barrel. The construction as a rule is stout enough to permit this. When the door is closed and locked in position the barrel is, to all intents and purposes, as far as this invention is concerned, a continuous and tight cylinder. This cylinder has mounted therein, the 70 plunger head, 15, constructed of the mushroom or inverted cup shape shown in drawings at Fig. 4. It is provided with the flange, 16, to act as a follower guide. The boss, 17, is tapped and threaded to receive 75 the end of the rod, 18. This rod is screwed rigidly into the boss, 17, and may be pinned in such position if desired, and if it is found necessary to prevent the same becoming separated from the rod, 18, when the same is rotated in the direction which would unscrew 80 the rod from the boss.

The rod, 18, passes through a smooth 85 bored perforation in the nipple, 7. The nipple, 7, is provided with a set screw, 19, 90 threaded in a tapped perforation in the head, 20, with which the nipple is provided. The purpose of the screw, 19, is that when driven home it impinges upon the rod, 18, and thereby causes the rod to advance or recede, 95 as the nipple, 7, is screwed in the boss, 6, and thereby advance or recede the plunger, 15. When this nut, 19, is released the rod, 18, may be freely moved through the perforation in the nipple, 7. 100

When the implement is used for lubricating with oil, it is found expedient to provide a gasket for the door, 9. It is for this purpose that I have provided the groove, 21, shown in Fig. 3 around the top of the opening. This groove would receive a gasket, which would be compressed by the door when screwed into its closed position.

The operation of the invention is best described in its two-fold use. Its greatest novelty is that in which it is employed for use in lubricating with heavy grease, such as "Albany", or similar lubricants. In such use the door, 9, is opened and the grease is 110

packed into the barrel, 2, completely filling the entire space, the plunger, 15, having been withdrawn to the top of the barrel to accommodate it. When it is packed the door, 9, is brought into position and the spring bolt, 13, carrying the nut, 12, is thrown over the yoke, 14, and the door secured firmly in position.

As stated the plunger, 15, has been withdrawn to the top of the barrel, and to do this the nut, 19, has been unscrewed and the rod, 18, drawn back. With the parts in position as has been described, the first operation is to force the plunger by means of the rod, 18, downward. This action packs the grease, and starts the same into the nozzle, 5. However, if the grease is not of a very light character the force applied would not eject the grease through the nozzle, 5. For this purpose the nipple, 7, is provided. The nut, 19, is screwed into engagement with the rod, 18. The nipple, 7, is now locked by the screw, 19, to the rod, 18. By now rotating the rod, 18, the threads of the nipple, 7, feed inward, carrying the rod, 18, and plunger, 15, forward at a slow rate but with powerful force sufficient to drive the grease out of the barrel, 2, and out of the small feed end of the nozzle, 5. The grease has been thus forced out until the end of the nipple, 7, is against the cap, 3. The rotation is now reversed and the nipple, 7, with the rod, 18, and plunger receded outward to the limit of action of the nipple, 7. The screw, 19, is then unscrewed, releasing the rod, 18, which is freely advanced as a plunger until the head, 15, rests on the packed grease when the screw, 19, is again tightened and the parts are again in position to repeat the operation as above described. By successive repetitions of this operation the barrel, 2, is finally evacuated of the grease.

When it is desired to use oil, the packing above referred to is placed in the groove, 21, and the cover, 19, is securely locked in closed position. The screw, 19, is unscrewed to release the rod, 18. The rod and plunger, together with the barrel, 12, of the nozzle, 5, are then operated as in any of the well-known squirt-gun, or syringe constructions.

Having thus described this invention, it is claimed:—

1. A lubricator comprising a cylindrical body portion having a delivery spout; a cap adapted to close the rear end of said body portion provided with a screw threaded central perforation; a screw threaded force feed member thread engaged with the perforation in said cap and having a longitudinal smooth perforation extended therethrough; a piston rotatably guided within said body portion, a smooth piston rod slidably mounted in the perforation in said feed

member; and means for locking the said rod and feed member in fixed relation.

2. A lubricator comprising a cylindrical body portion having a delivery spout; a hinged section for the body portion; locking means to rigidly hold said hinged section in position to conform to the cylindrical surface of said body portion; a cap adapted to close the rear end of said body portion provided with a screw threaded central perforation; a screw threaded feed member thread engaged with the perforation in said cap and having a longitudinal smooth perforation extended therethrough; a piston rotatable within said body portion; a smooth surfaced rod slidably mounted in the perforation in said feed member; and means for locking the said rod and feed member in fixed relation.

3. A lubricator comprising a cylindrical body portion provided with a delivery spout; a longitudinal section of said body portion being hinged to the main section of the body portion and adapted to fit said main section when closed to preserve the cylindrical shape of the interior of said body portion; a suitable fastening device to secure the free end of said removable section to lock the said section firmly in position; a cap adapted to close the rear end of said body portion provided with a screw threaded central perforation; a screw threaded member adapted to engage the perforation in said cap and having a longitudinal perforation extended therethrough; a plunger having a circular head rotatable within said body portion, and a smooth rod slidably mounted in the perforation in said screw threaded member; and means for locking the said rod and screw threaded member in fixed relation.

4. A lubricator comprising a cylindrical body portion provided with a delivery spout at the forward end and closed at the rear end to provide a screw threaded perforation in said closing member; a screw threaded member adapted to engage the said screw threaded perforation in the rear end of said body portion and having a longitudinal perforation; a plunger embodying a head rotatable in said body portion, and a smooth rod slidably mounted in said perforation in said screw threaded member; and a set screw mounted in said threaded member adapted to impinge upon the said plunger rod to hold the same in fixed relation with the said threaded member.

Signed at New York in the county of New York and State of New York this 2nd day of November A. D. 1908.
